UNITED STATES PATENT OFFICE.

BENJAMIN F. McGUINNESS, OF SAUNDERSVILLE, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-REPLENISHING LOOM.

Application filed December 4, 1925. Serial No. 73,245.

This invention relates to a weft replenishing loom of the pick and pick type, that is, to an automatic loom in which any one of the shuttles may be picked in either direction at any time, as distinguished from looms in which each shuttle must make at least two successive picks whenever it comes into operation.

It is the general object of my invention to provide a weft-replenishing, pick and pick loom in which approaching weft exhaustion is indicated at the non-replenishing side of the loom and in which the weft is automatically replenished at the opposite or magazine side of the loom.

It has been noted in prior automatic pick and pick looms that a weft carrier is frequently transferred to a shuttle which thereafter remains inactive for a longer or shorter time, while some other shuttle becomes active. This delay of the replenished shuttle frequently causes breakage of the weft end which leads from the shuttle to the stationary end holder of the loom. This weft breakage is particularly liable to occur on account of the fact that the weft thread is not actually threaded into the shuttle eye until after the replenished shuttle has made its flight across the lay.

Accordingly, another object of my invention is the provision of mechanism by which a weft transfer can be effected only to a shuttle about to become active. This I consider to be a feature of my invention which is of very great importance.

My invention further relates to the provision of a mechanical feeler of a new and improved construction, to an improved transferring mechanism, and to the provision of means including a special pattern chain construction by which the mechanical feeler may be operatively positioned with relation to a shuttle about to become active.

My invention further relates to arrangements and combinations of parts which will be hereinafter described and more particularly pointed out in the appended claims.

A preferred form of the invention is shown in the drawings in which

Fig. 1 is a left hand side elevation of the magazine and its operating mechanism, with the lay and breast beam indicated in section;

General description of the loom.

As shown in the drawings, the loom is provided with three shifting shuttle or drop boxes at each side of the loom. A three-color magazine is shown at the right hand side of the loom and the usual drop box operating mechanism is provided at the left side of the loom. A mechanical feeler is also provided at the left hand side of the loom and is movable by pattern controlled devices into position to co-operate with any selected shuttle box.

The pattern mechanism is so designed that the feeler will be positioned to co-operate with the shuttle which is about to become active. Provision is also made by which the feeler, after being thus positioned, will move with the associated shuttle as it is raised or lowered to picking position. A transfer mechanism is provided at the magazine side of the loom and is adapted to transfer a weft carrier horizontally to the shuttle which is about to become active.

Referring to the drawings, I have shown portions of a loom frame 30 (Fig. 2) on which is mounted a lay 31 actuated by the usual crank shaft 32 and connecting rod 33. Drop boxes 34 are mounted on the left hand or detecting end of the lay and these boxes are movable vertically by drop box actuating mechanism of any usual or commercial type.

As shown in the drawings, a lifter rod 35 is connected to a lever 36 having a floating center 37 and supported by angle levers 40 and 41, which in turn are connected by links 42 and 43 to vibrator gears 44 which are intermittently actuated by the usual cylinder gears 45 and 46. The vibrator gears are mounted on vibrator levers 47 which are connected by links 48 to the usual pattern controlled levers 49 (Fig. 8). A suitable give-way connection is preferably provided between the two parts of the floating lever 36.

Similar drop boxes 50 (Fig. 11) are pro-

vided at the magazine end of the loom and suitable connections to be described cause the two sets of drop boxes to raise and fall simultaneously.

Detecting mechanism.

The detecting mechanism is shown on an enlarged scale in Figs. 6 and 7 and comprises a detecting member or feeler 60 mounted for both sliding and swinging movement in a stand 61 which is pivoted at its forward end upon a stud 62. The stud 62 is mounted in an arm 63 which in turn swings about a fixed pivot or stud 64. The detecting member 60 is of the well known side slip type and is pressed yieldingly rearward by a spring 65. A cross piece 66 secured to the detector 60 engages an inclined bearing surface 67 on the stand 61 and normally positions the detector 60 as shown in Fig. 6.

When the detector engages a substantially exhausted weft carrier, the detector slides along the relatively smooth surface of the bobbin or weft carrier toward the right, thus projecting a plunger 68 (Fig. 4) into the path of an actuating member 69 (Fig. 3). This member 69 is connected by a bell crank 70 and link 71 to a lever 72 which is rocked by a cam 73 on every pick of the loom, thereby causing the member 69 to move forward. If the plunger 68 is projected into the path of the member 69, the plunger 68 and its supporting member 74 are pushed forward, rocking the arm 75 to which the member 74 is connected and thus turning the shaft 76 on which the arm 75 is mounted.

The shaft 76 extends across the front of the loom to the magazine side where it is provided with an arm 77 (Fig. 1) connected to a rod 78 which controls the indication of weft exhaustion to the magazine as will be hereinafter described.

Attention is called to the universal joint connections between the plunger 68 (Fig. 6) and the detector 60, which permit the plunger 68 to be swung forward for transfer indication and also permit the stand 61 to be moved to different vertical positions as will now be described.

Detector positioning devices.

The arm 63 (Fig. 6) which supports the stud 62 is connected by a yielding link 80 (Figs. 6 and 8) to a lever 81 mounted on the stud 82 (Fig. 8) fixed to the loom frame 30. An indicating lever 83 (Fig. 8) is pivoted at 84 on a fixed bracket 85 and is connected by a link 86 to the lever 81. The lever 83 is connected at its opposite end by a link 87 to a pattern lever 88 which cooperates with a portion of the drop box pattern chain 89 (Fig. 2).

The stand 61 (Fig. 6) is similarly con-

5 nected by a yielding link 90 (Fig. 7) to a lever 91 pivoted at 82 and connected by a link 93 (Fig. 2) to an indicating lever 94 mounted on a fixed pivot 95. The lever 94 is connected by a link 96 to a second pattern lever 97, as in the connections previously described.

10 The pattern chain 89 (Fig. 2) for controlling the pattern levers 88 and 97 is preferably provided with chain rolls of three different diameters as indicated at 100, 101, 102 in Fig. 10.

15 In the arrangement marked A, two of the medium size rolls 100 position the stand 61 to co-operate with a shuttle which is positioned level with the shuttle race. In the arrangement B, I use a medium roll 100 to position the connector 90 for the stand 61 and a large roll 101 to position the connector 20 80 for the arm 63. This moves the stand 61 so that the detector will co-operate with a shuttle which is positioned one space below the shuttle race. Similarly, a medium roll 100 combined with a small roll 102, 25 as in arrangement C, causes the stand 61 to be positioned so that the detector will co-operate with a shuttle which is one space above the running position. Two large rolls 101 will raise the stand 61 as indicated in 30 arrangement D, so that the detector will co-operate with a shuttle which is two spaces above the running position and similarly a combination of two small rolls 102, as shown in arrangement E, will position the stand 35 61 so that the detector will co-operate with a shuttle which is two spaces below the running position.

40 By the use of two indicating levers and a chain constructed as above described, I am thus able to give the detector five different operative positions. The pattern chain 89 (Fig. 2) is intermittently moved ahead approximately one half pick earlier than the drop box mechanism.

45 The detector stand 61 (Fig. 6) is provided with a rearwardly extending stud or projection 106 adapted to enter any one of a series of holes 107 (Fig. 7) in a strap or bracket 108 fixed to and movable with the 50 drop boxes 34. The stand 61 and projection 106 are positioned as above described just prior to the forward movement of the lay and such forward movement causes the projection 106 to enter that one of the holes 55 107 which is associated with the selected shuttle box which is about to supply the running shuttle.

60 The detector 60 will thus be held in operative relation with the selected shuttle as the drop boxes rise or fall, the stand 61 being swung upward or downward by its connection through the projection 106 to the shuttle box and such swinging movement being permitted by the yielding con-

65 struction of the links 80 and 90, as indicated in Fig. 7.

I have thus provided a mechanical weft detector or feeler which will be moved in advance to co-operate with the shuttle which is about to become active. If this shuttle 70 is thereafter raised or lowered to bring it to operative position, the detector will swing with the drop boxes and will maintain its operative detecting relation to the weft carrier in the shuttle. If the weft carrier is 75 substantially exhausted, the detector will slip side-ways, advancing the plunger 68 (Fig. 4) into the path of the actuating member 69 and rocking the shaft 76 to indicate weft exhaustion. A lost-motion slotted connection (Fig. 6a) between the detector 60 and the plunger 68 prevents movement of the latter by the ordinary forward movement of the detector.

Weft replenishing magazine.

85

The magazine 110 (Fig. 1) is in general of the usual multicolor stationary magazine type and is shown herein as providing for the use and control of three different kinds 90 or colors of weft carriers. The usual color slide 111 is connected by a bell crank 112, connector 113 and other connections (not shown) to the drop box actuating mechanism so that the magazine will always be set to 95 release a weft carrier corresponding in color to the running shuttle, this being the usual arrangement in weft replenishing drop box looms.

100 For a detailed description of the type of mechanism shown in the drawings, reference is made to the prior patent to Ryon, No. 1,030,748 issued, June 25, 1912.

The color slide is arranged to be rocked by a link 114 (Fig. 1) upon indication of weft exhaustion, which is evidenced by projection of the plunger 78 (Fig. 1) into the path of a floating lever or actuator 115 (Fig. 22) which is rocked at every pick by a link 116 (Fig. 1) and cam lever 117, actuated in turn by a continuously rotating double cam 118.

115 Upon indication of weft exhaustion, a bobbin of the selected color is released by the rocking movement of the color slide and is advanced to intermediate position, but its further advance to transfer position is controlled by additional mechanism, as will be hereinafter described, so that the transfer 120 does not occur until just prior to the flight of the replenished shuttle from the magazine end of the loom.

Transferring mechanism.

125 The transferring mechanism in my improved loom is arranged to transfer the bobbin horizontally through the front side of the shuttle box and to eject the exhausted

- bobbin through an opening in the rear side thereof. The transferring mechanism is movable vertically to bring it into co-operation with the shuttle box which is about to be positioned at the level of the shuttle race.
- For this purpose the bobbin holder and transerrer are supported and actuated in a manner similar to the arrangement for the weft detector stand 61, the bobbin holder being swung vertically simultaneously with the detector stand.

Referring particularly to Figs. 15 to 18, the bobbin holder 120 (Fig. 15) is provided with forwardly projecting arms 121 pivoted on studs 122 in the swinging forward ends of arms or levers 123 which in turn are mounted upon fixed pivot studs 124. The left hand arm 121 is connected by a yielding link 125 (Fig. 12) to a lever 126 (Fig. 11) pivoted at 127 and connected by a link 128, a bell crank 129 (Fig. 15^a), an adjustable connecting rod 130, a bell crank 131 and a link 132 to the lever 91 (Fig. 8) by which the detector stand 61 is positioned.

The arm 123 (Fig. 15) is similarly connected through a yielding link 133 (Fig. 12), a lever 134 and a link 135 (Fig. 13) to duplicate bell cranks and connecting rods through which connection is made to a link 136 (Fig. 8) pivoted at its upper end on the lever 81 which positions the arm 63 on which the detector stand 61 is pivoted.

By these connections the bobbin holder 120 is swung about its centers 122 and 124 (Fig. 15) to any one of five different positions corresponding to the positions A, B, C, D and E of the weft detector as indicated in Fig. 10. This positioning movement takes place shortly prior to the movement of the drop boxes and associates the bobbin holder and transerrer with the shuttle box about to assume active or running position and about to receive the indicated shuttle.

The bobbin holder 120 is provided with a flat bottom portion 140 (Fig. 15) and with side flanges 141 (Fig. 18) which are grooved to furnish guide-ways for the transerrer 142. A lug 143 (Fig. 15) on the side of the bobbin holder 120 is provided with an adjustable stud 144 which projects rearward and is adapted to enter one of a series of guide openings 145 (Fig. 20) in a strap or bracket 146 secured to the frame 147 of the drop boxes 50 at the magazine side of the loom.

These drop boxes are supported by the usual lifter rod 148 which is shifted vertically in unison with the lifter rod 35 at the opposite side of the loom through connections indicated diagrammatically in Fig. 21. These connections comprise an arm 149 mounted on a rock shaft 150 and connected to the lower end of the lifter rod 148. A second arm 151 is connected to the lifter rod 35 (Fig. 2) so that the two sets of drop

boxes will move together and that corresponding shuttle boxes on opposite sides of the loom will always lie in the same horizontal plane.

As the boxes are shifted, the stud 144 and strap or bracket 146 keep the bobbin holder and transerrer in operative relation with the selected shuttle box during the vertical shifting movements of the boxes.

Transerrer actuating mechanism.

The transerrer 142 is actuated to force the bobbin rearward in the bobbin holder 140 and thereby effect transfer to the exhausted shuttle. For this purpose, the transerrer is provided with a forwardly extending arm 154 (Fig. 15) forked to receive the slotted upper end of a transfer lever 155 (Fig. 13) mounted upon a fixed pivot 156 and having an elongated slot at its upper end through which extends a stud 158 (Fig. 17), mounted in the forked arm 154 of the transerrer 142. This slotted connection between the transerrer and the transfer lever provides a continuous operative connection, while permitting angular movement of the transerrer with the bobbin holder.

At its lower end the lever 155 (Fig. 11) is provided with a latch 160 which is normally positioned out of the path of movement of a bunter 161 by which it is actuated to transfer a bobbin. The bunter 161 is preferably fixed to the front end of a rod 162 (Fig. 11) slidable in a bearing 163 and having a pin and slot connection at its rear end to a lever 164 actuated by a cam 165 on the bottom or cam shaft 166. This cam 165 is preferably double-acting, as shown in the drawings, so that the bunter 161 is moved forward at every pick of the loom.

The latch 160 is controlled through a link 166^a (Fig. 11) from the upper shaft 168 (Fig. 1) of the magazine, which is actuated in the usual manner to raise the latch when the bobbin is released from intermediate position and is allowed to drop into the bobbin holder. The operation of these parts is clearly described in the patent to Ryon, 1,030,748 previously cited.

Bobbin support and release.

The bobbin holder 120 (Fig. 15) is provided with a door or trap 170 (Fig. 17) in the bottom 140 thereof, upon which trap the bobbin B rests while awaiting transfer. The bobbin is retained in this position by yielding spring clips or retainers 171 and 172 (Fig. 18). The trap 170 is held normally closed by springs 173 and 174, the closed position being regulated by an adjusting screw 175 (Fig. 17).

A depending rod 176 is pivoted at 177 to the trap 170. The rod 176 is slidable through a recess 177^a in a plate 178, pivoted

to the upper end of an actuating rod 179. The rod 179 is moved vertically at every pick of the loom in some convenient manner as by a suitable connection (not shown) to the cam lever 164.

When in its upper position, the plate 178 engages a stop pin 180 (Fig. 17) and is thereby moved to horizontal position against the tension of a spring 181 by which it is normally swung upward about its pivot on the rod 179. When the plate 178 is in horizontal position, the rod 176 is freely slideable through the opening 177 as the bobbin holder and transerrer are moved vertically with the drop boxes. When the rod 179 is depressed, however, the plate 178 swings angularly to grip and depress the rod 76, thus opening the trap 170 and releasing the bobbin resting thereon, if for any reason the bobbin has failed to be transferred.

Shuttle box construction.

The shuttle boxes at the magazine side of the loom are of special construction to permit horizontal transfer of the bobbins. Referring to Figs. 19 and 20, it will be seen that the lay end 183 is provided with a large rear opening 184 through which the exhausted bobbins may be ejected. The extreme outer portion of the lay end 183 is also slotted as indicated at 185 to provide a continuation of the opening 184 through which any trailing weft ends may be drawn out of the path of an in-coming shuttle.

A drop box frame 147 for the boxes 50 is similarly provided with a series of rear openings 186, one opening being positioned opposite each of the boxes. The shuttle binders 187 (Fig. 16) are also provided with openings 188 and with a narrow slot 189 between the upper and lower parts of the binder. The binders are provided with the usual springs 190 which, are forked to engage the upper and lower portions of the binders and to prevent obstruction to the transfer of the bobbins. Each shuttle box 50 has a large opening 191 at its front side, as shown in Fig. 23, and also has a slot 192 at the inner end thereof, between the front side of box plate and the top of the shuttle box.

These narrow slots 189 and 192 permit the weft thread W attached to a transferred bobbin to be drawn entirely free of the binder and shuttle box as the latter moves rearwardly and the shuttle is picked from the box the end of the weft thread being still attached to the weft end holder and the shuttle being not yet threaded. (See Fig. 24). The chance of weft breakage is thus substantially reduced.

Having described the construction of my improved loom, I will now indicate briefly the method of operation thereof.

The detector stand 61 and the bobbin

holder 120 are moved through connections from the indicator levers 88 and 97 so that they are positioned in alignment with that shuttle which is about to become active, this positioning occurring in advance of the shifting of the drop boxes. During the shifting of the drop boxes, the boxes also move forward and the detector, being retained in operative relation with the shuttle about to become active, thereupon indicates the condition of the weft supply therein. If the weft is substantially exhausted, the detector will slip along toward the tip of the bobbin, advancing the plunger 68 (Fig. 4) into the path of the actuator 69 (Fig. 3) and thus causing movement of the rock shaft 76, thereby rendering the actuator rod 116 (Fig. 1) effective to rock the color slide 111 which is maintained in selective position corresponding to the running shuttle by its connection to the pattern levers which control the drop boxes.

A fresh bobbin is thus advanced to intermediate position before the exhausted shuttle is received at the magazine side of the loom. The bobbin is held in its cradle in intermediate position until the exhausted shuttle has been sent to the magazine side of the loom and until the substantially exhausted shuttle is about to again become active. At this time the color slide 111 will again be moved to a position corresponding to the partially released bobbin, and the rocking of the color slide will fully release the bobbin and will allow it to fall into the bobbin holder, at the same time raising the latch 160 into the path of the bunter 161. This selective axial movement of the color slide and also its rocking movement occurs on every pick of the loom, instead of on every second pick, which is the usual arrangement. The axial movement is preferably controlled from the drop box pattern and takes place just prior to the rocking movement thereof. In other words, the color slide is moved to a position corresponding to the shuttle next to be picked just prior to the actuation of the mechanism for finally releasing the bobbin and for raising the latch 160 to operative position.

As the bunter thereupon advances, the transerrer 142 will be moved rearward and such movement, combined with the forward movement of the lay, will cause the fresh bobbin to be inserted in the exhausted shuttle and the spent bobbin to be ejected through the rear opening of the drop boxes and lay end.

By the mechanism above described, I am thus able to effectively transfer a fresh bobbin to a substantially exhausted shuttle and to make such transfer just prior to the picking of the replenished shuttle from the magazine side of the loom. This latter result is particularly important, as it prevents

transfer of a bobbin to a shuttle which is about to remain idle at the magazine side of the loom for a longer or shorter period of time, during which time the fresh weft 5 end would very probably be broken by the movement of the lay while the end was attached to the fixed end holder of the loom.

If the bobbin fails of transfer, the revoking mechanism opens the trap 170 in the 10 bobbin holder 140 and thus removes the untransferred bobbin.

Having thus described my invention and the advantages thereof, I do not wish to be limited to the details herein disclosed otherwise than as set forth in the claims, but 15 what I claim is:—

1. A weft replenishing drop box loom having, in combination, shifting shuttle boxes, a magazine, weft replenishing mechanism associated therewith, a single weft detector, means to move said weft detector into position to enter any selected shuttle about to become active, and means to thereafter 20 positively connect said detector with the shuttle box of the selected shuttle and to positively maintain operative relation between the weft detector and said shuttle during the vertical shifting of the boxes.

2. A weft replenishing drop box loom 25 having, in combination, a magazine, weft replenishing mechanism associated therewith, a weft detector mounted for vertical swinging movement about a pivot stud, a supporting member for said stud mounted to 30 swing about a fixed pivot, selective means to move said supporting member to cause said weft detector to enter any selected shuttle about to become active, and means to maintain said weft detector in operative relation with said shuttle while said shuttle 35 is moved vertically to running position.

3. A weft replenishing drop box loom 40 having, in combination, a weft detector, a stand for said detector, a movable supporting member to which said stand is pivoted, selective means to move said supporting member, and additional selective means to move said stand about its pivot on said member, whereby said detector may be brought 45 into operative relation with a shuttle in a plurality of different vertical positions.

4. A weft replenishing drop box loom having, in combination, a transferrer at the 45 replenishing side of the loom, a weft detector at the non-replenishing side of the loom, and means to give said transferrer and said detector simultaneous selective movements to associate said parts with the drop boxes corresponding to the shuttle about to become 50 active.

5. A weft replenishing drop box loom having, in combination, a plurality of vertically shifting drop boxes, a weft detector, pattern controlled mechanism effective to move said 55 detector into co-operative relation with a

selected drop box, a recessed member on said drop boxes and a plunger associated with said weft detector, effective to enter a recess in said member as the boxes move forward and to thereafter maintain such relation during the subsequent shifting of the boxes. 70

6. A weft replenishing drop box loom having, in combination, a plurality of vertically shifting drop boxes, a weft detector, pattern controlled mechanism effective to swing said detector about two different centers to move said detector into co-operative relation with a selected drop box, and means to thereafter maintain such relation during the subsequent shifting of the boxes. 75

7. In a weft replenishing drop box loom, a magazine, a plurality of vertically shifting shuttle boxes on the magazine side of the loom, a bobbin holder, a transfer mechanism effective to transfer a bobbin substantially 80 horizontally from said holder to a shuttle in a selected drop box, and means to postpone such transfer until a pick on which the replenished shuttle is to remain active.

8. In a weft replenishing drop box loom, 85 weft detecting mechanism effective to indicate weft exhaustion in a shuttle about to move to active running position, means to thereafter transfer a bobbin to said shuttle, and means to postpone such transfer until a pick on which the replenished shuttle is to 90 be sent to the non-replenishing side of the loom.

9. In a weft replenishing drop box loom, 95 in combination, a magazine, a transerrer, actuating mechanism for said transerrer, and pattern controlled means to postpone actuation of said transerrer until a pick on which the shuttle receiving the fresh bobbin is to remain active. 100

10. In a weft replenishing drop box loom, in combination, a magazine, a lay, a set of vertically shifting shuttle boxes at each end of the lay, a weft detector at the non-replenishing side of the loom movable substantially vertically to co-operate with a selected shuttle box, a transfer mechanism at the magazine side of the loom also movable substantially vertically to co-operate 110 with a selected shuttle box, and pattern controlled means effective to cause simultaneous selective movements of said detector and said transfer mechanism. 115

11. In a weft replenishing drop box loom, in combination, a magazine, a lay, a set of vertically shifting shuttle boxes at each end of the lay, a weft detector at the non-replenishing side of the loom movable vertically to co-operate with a selected shuttle box, a transfer mechanism at the magazine side of the loom also movable vertically to co-operate with a selected shuttle box, and pattern controlled means effective to cause simultaneous selective movements of said detector and said transfer mechanism, said 120 125 130

- selective movements taking place in advance of the shifting movements of the drop boxes by which the selected shuttle is moved to running position.
- 5 12. A weft replenishing drop box loom having, in combination, a magazine, a lay, a set of vertically shifting shuttle boxes at each end of the lay, said sets of boxes maintaining a fixed relation to each other, means to shift 70 said sets of boxes simultaneously, means to indicate substantial exhaustion of weft on the non-replenishing side of the loom, a vertically adjustable, horizontally acting transerrer on the magazine side of the loom, and means to adjust said detector and said transerrer simultaneously vertically to positions corresponding to the position of the shuttle about to become active.
- 10 13. In a weft replenishing drop box loom, a bobbin holder, a transerrer mounted thereon, means to move said transerrer in a substantially horizontal direction to eject a bobbin from said bobbin holder, said holder having a trap in the bottom thereof, and means to periodically open said trap to release a bobbin failing of transfer therefrom.
- 15 14. In a weft replenishing drop box loom, a bobbin holder, a transerrer mounted thereon, means to move said transerrer in a substantially horizontal direction to eject a bobbin from said bobbin holder, said holder having a trap in the bottom thereof, and means to periodically open said trap to release a bobbin failing of transfer therefrom, 90 said opening means including a connection permitting free vertical adjustments of said bobbin holder between releasing movements of said opening means.
- 20 15. In a weft replenishing drop box loom, a feeler stand, a pair of indicating levers connected to selectively position said feeler stand, and a pattern chain effective to actuate said levers and having elements engaging said levers at three different elevations.
- 25 16. In a weft replenishing loom, a weft detector, a pair of indicating levers connected to selectively position said detector, and a pattern chain for moving said levers, said chain having engaging elements of relatively large, small and intermediate diameters.
- 30 17. In a weft replenishing drop box loom, a plurality of drop boxes each having openings in the front and rear box plates thereof, and a separate front binder permanently associated with each box and having a corresponding opening therethrough and having a slot communicating with said opening, said slot being at the free end of the binder adjacent the cloth selvage.
- 35 18. In a weft replenishing drop box loom, a plurality of drop boxes having openings in the front and rear box plates thereof and a separate front binder permanently associated with each drop box and having upper and lower portions positioned to engage portions of the shuttle, said binder portions being entirely separated at the free end of said binder adjacent the cloth selvage, and the opening in the front box being unobstructed 70 at its corresponding end.
- 40 19. In a weft replenishing loom, a magazine, a lay, and a shuttle box at the magazine end of the lay, said shuttle box having an opening in its front box plate to permit horizontal transfer of a bobbin therethrough, and said opening being unobstructed at the end adjacent the cloth selvage, permitting free escape of the weft end from said box.
- 45 20. In a weft replenishing loom, a magazine, a lay, and a shuttle box at the magazine end of the lay, said shuttle box having an opening in its front box plate to permit horizontal transfer of a bobbin therethrough, and said opening communicating with a slot adjacent the top of the box and at the end of the box adjacent the cloth selvage, permitting free escape of the weft end from said box.
- 50 21. In a weft replenishing loom, a magazine, a lay, a shuttle box at the magazine end of the lay having an opening in its front box plate to permit horizontal transfer of a bobbin therethrough, and a binder having a corresponding opening therein, said binder and box both having provision to permit the escape of a weft end from said shuttle box as the shuttle is picked therefrom.
- 55 22. In a weft replenishing loom, a multi-color magazine, an end holder, and a plurality of vertically movable drop boxes at the magazine side of the loom, said boxes having openings therein permitting horizontal transfer of bobbins to shuttles in said shuttle boxes, and said boxes being constructed to permit free escape of the weft ends from said boxes at the ends thereof adjacent the cloth selvage, whereby the weft 105 extends free from said end holder to said selvage after the flight of a replenished shuttle from one of said boxes.
- 60 23. In a weft replenishing drop box loom, a magazine, a bobbin holder movably mounted beneath said magazine, pattern controlled means to give said bobbin holder a selective vertical movement, means to transfer a bobbin substantially horizontally therefrom to a substantially exhausted shuttle, 110 and means to release a bobbin remaining in said holder through revoking of the transfer.
- 65 24. In a weft replenishing drop box loom, a bobbin holder, means to transfer a bobbin substantially horizontally therefrom to a substantially exhausted shuttle, means to change the vertical position of said bobbin holder to cooperate with different shuttles, and means to release a bobbin remaining in said holder through revoking of the trans- 115
- 70 130

fer, said means being operative in every vertical position of said holder.

25. In a weft replenishing drop box loom, a bobbin holder, means to transfer a bobbin substantially horizontally therefrom to a substantially exhausted shuttle, means to change the vertical position of said bobbin holder to cooperate with different shuttles, a trap in said bobbin holder, and means to open said trap in every vertical position of said bobbin holder.

26. In a weft replenishing drop box loom, a magazine, weft replenishing mechanism adjacent thereto, a weft detecting mecha-

nism located at the non-replenishing side of 15 the loom and effective to indicate weft exhaustion in a shuttle about to move to active running position, and means to postpone the operation of the weft replenishing mechanism after indication by said detecting 20 mechanism until the indicated shuttle is received at the magazine side of the loom and is about to be sent to the non-replenishing side of the loom.

In testimony whereof I have hereunto 25 affixed my signature.

BENJAMIN F. McGUINNESS.
